UNITED STATES PATENT OFFICE.

JOHN D. DALE, OF PHILADELPHIA, PENNSYLVANIA.

PLANING-MACHINE.

Specification of Letters Patent No. 18,806, dated December 8, 1857.

To all whom it may concern:
Be it known that I, JOHN D. DALE, of the city of Philadelphia, in the Commonwealth of Pennsylvania, have invented a new and useful Machine, which I have entitled the "Universal Planing, Molding, and Sash Machine," and which is intended to perform the following descriptions and varieties of work: First, truing or taking boards, planks, and other carpenter stuff out of wind; second, planing, tonguing, and grooving boards and planks; third, making boards, planks, &c., into several moldings at once, either of the same or various patterns, and separating each molding; fourth, making boards, planks, &c., into sash-stuff and tenoning the same; fifth, doing other tenoning-work; sixth, working circular moldings and doing circular work of every description; and I do hereby declare that the following is a full, clear, and exact description of the construction and various operations of the same; reference being had to the annexed drawings, which are made part of this specification, in which—

Figure 1 is a transverse sectional view. Fig. 2 is a view of the upper portion, taken from above. Fig. 3 is a horizontal-sectional view of the lower portion. Fig. 4 is a perspective view with the carriage extended. Fig. 5 is a perspective view with the carriage retracted.

The separate parts or portions of the machine are marked and numbered as follows: A, A, are the stands or sides which form the framework that supports the various portions of the machinery.

B, B, the bedpiece which is suspended by the rods Y, Y, whose upper extremities passing through the caps V, V, are cut into screw-threads, upon which work the worm nuts W, W, revolved by the transverse screw shaft X, thus enabling the bedpiece to be elevated or depressed at the pleasure of the operator. This bedpiece is kept in a perfectly horizontal position at whatever height it may be raised to, by means of the toggle jointed levers 6 $\frac{1}{2}$, 6 $\frac{1}{2}$, 6 $\frac{1}{2}$, 6 $\frac{1}{2}$, which are connected together by the braces Nos. 6 and 6.

C, the interior feed roller, furnished with cogged-gear wheels to fit into the rack on the under surface of the carriage E, E.

D, the upper or superior feed roller into

the journal-boxes of which Nos. 45, the rods U, U, attached to the weighted levers T, T, are inserted, so that the weights Nos. 42 exert a pressure upon the roller and consequently upon the stuff as it passes beneath when the machine is used with the continuous feed, in which operation the periphery of the roller is on a level with the lower edge of the knives of the cutting head. This arrangement admits of the rollers being elevated by means of the levers T, T. One end of the elbow lever No. 38, whose other end is attached to arm P, on the pressure bar Q, as hereinafter described, rests on the journal boxes of this roller (Nos. 45 and 45) as does also one end of the lever M, whose fulcrum is attached to the frame work A, A. This lever M raises the back pressure bar N, and the effect of this arrangement is, that by simply raising the weighted levers T, T; this roller D, the transverse bar Q with its mouth pieces R, R, R, R, and the back pressure bar N, are all simultaneously elevated to any height above the edge of the cutting head that may be necessary.

E, E, the carriage frame with the cog-rack upon its under surface, and a recess at each end to admit the insertion of a movable and adjustable cutting bed No. 37; and a stub or pin on which the hook of rod No. 10 catches as hereinafter set forth.

F, the wooden bed of the carriage.

G, G, the cranes supporting the side cutters; hanging upon the arms K, K. These cranes may be swung around back and forth, and adjusted and secured by means of the guide braces L, L, and the screw nuts No. 40, 90 and may be elevated and depressed at pleasure, thus elevating and depressing the side cutters by means of the screw-nuts J, J.

H, H, the side cutter heads used for tonguing, grooving, tenoning, etc.

I, I, counter-shafts for driving the side cutters by means of straps.

J, J, screw-nuts for raising or depressing the side cutter heads as before described.

K, K, arms, bolted on frame A, A, cut with screw holes through which pass the countershafts I, I, upon which work the screw nuts J, J.

L, L, guide braces for securing the side cutter heads H, H, in the required positions, 105 and preventing lateral motion.

M, guide lever for elevating and holding up the back pressurebar N, resting upon, and worked by the elevation and depression of the superior feed roller D, as hereinbefore mentioned.

N, the back-pressure-bar for preventing back-lash.

O, guide-rod, regulating the direction and distance of the motion of the transverse bar Q.

P, arm of the bar Q with spring attached to the guiderod O, allowing the transverse bar Q to yield.

Q, a bar running transversely across the machine over the carriage supporting the mouth-pieces R, R, R, R.

R, R, R, R, adjustable mouth pieces, which should of course be made to fit and correspond with the various blades used in the main cutting head, so as to correspond in character with that of the work to be done.

S, S, upright rods or posts upon which the weighted levers T, T, are supported and pivoted.

T, T, levers with adjustable weights (No. 42) which communicate the pressure to the feed roller D, and by whose means the roller D, can be elevated at pleasure as herein before described.

U, U, perpendicular rods pivoted on the levers T, T, and inserted into the journal boxes (No. 45) of the feed roller, D. By these rods the pressure of the weighted levers T, T, is communicated to the feed roller D.

V, V, caps, upon which are pivoted the upright rods S, S, and supporting the upright rods Y, Y, the worm nuts W, W, and the transverse screw shaft X, which serves to raise and depress the bed piece B, and the carriage C.

W, W, worm-nuts working on screw-threads cut upon the head of the rods Y, Y, and upon which the screw shaft X works.

X, the transverse screw shaft for elevating and depressing the bed B and carriage C.

Y, Y, perpendicular or upright rods inserted into the bed B. The upper end of these rods passing into and through the cap V are cut with screw threads on which the screw nuts W, W, work.

Z, Z, Z, Z, cogwheels connected together by pivoted bars (No. 1) so as to form a universal gear, by which the revolutions of the inferior feed roller C are communicated to the superior feed roller D.

No. 1, series of bars, connecting the cogwheels Z, Z, Z, Z, and forming a universal gear.

No. 2, adjustable guideboard by which the stuff can be guided into any operating part of the machine.

No. 3, arms supporting the rollers No. 17, elevated and depressed by the operation of the rods Nos. 4 and 5.

No. 4, brace rod, by which the arms No. 3, are connected and kept equidistant.

No. 5, lever rod, attached to arm No. 3 at one end, and at the other to the crank No. 7, by turning which crank the rollers No. 17 70 may be depressed through the operation of this lever rod and the brace rod No. 4, so as to allow the carriage to pass freely backward and forward over them when in use as a vibrating carriage, or when the carriage 75 is drawn out or extended while using a continuous feed they may be elevated to a level with the surface of the carriage, so as to form a support while working the stuff.

No. 6, brace rod, which serves to keep the 80 toggle jointed levers No. 6 $\frac{1}{2}$ equidistant.

No. 6 $\frac{1}{2}$, toggle jointed levers which connect the bed piece B with the framework A and keep the bedpiece B always horizontal.

No. 7, crank on the shaft No. 32, and attached to lever rod No. 5.

No. 8, cam, on shaft No. 32, which elevates one end of the lever No. 9, and thus draws down the rod No. 10, the upper end of which rod No. 10 is hooked in such manner that 90 when the carriage E is extended, this hook seizes the stub or projection on the side of the carriage, and drawing the carriage down secures it firmly in its place.

No. 9, the lever, described in No. 8, which 95 lever works.

No. 10, the hooked rod for securing the carriage as described in No. 8.

No. 11, feed pulley on shaft No. 30 which is strapped to and driven by pulley No. 26 100 on shaft No. 31.

Nos. 12, driving pulleys, which are strapped to, and drive the pulleys Nos. 24 on the countershafts I, I.

No. 13, comb feed pulleys on shaft No. 31, 105 which are strapped to and drive the pulley No. 16 on shaft No. 30.

No. 14, tight-and-loose pulley on shaft No. 31 by which the power is communicated thereto.

No. 15, lower portion of the cranes G, G.

No. 16, comb feed pulley on shaft No. 30, driven by pulley No. 13 on shaft No. 31. This pulley is provided with a spiral spring or other elastic substance inside to prevent 115 the sudden jar when the clutch No. 28 is thrown in.

No. 17, support rollers on bed piece B.

No. 18, hand wheel for turning shaft X.

No. 19, caps, forming seats for the boxes 120 of the cutter heads.

Nos. 20, 21, 22, 23, cogwheels connected by pivoted bars No. 41, so as to form a universal gear, whereby the motion of the shaft No. 30 (upon the end of which is fastened 125 the wheel No. 23), is communicated to the inferior feed roller C by means of the cog-wheel No. 21.

No. 24, pulleys on the countershafts I, I. strapped to and driven by pulleys Nos. 12. 130

No. 25, pulley on shaft No. 29, driven by pulley No. 27 on shaft No. 31.

No. 26, pulley on shaft No. 31, which drives pulley No. 11, on shaft No. 30. By 5 means of this the backward motion of the carriage is obtained.

No. 27, pulley on shaft No. 31 which drives pulley No. 25 on shaft No. 29.

No. 28, clutch, on shaft No. 30, which 10 clutching into pulley No. 16 on one side and No. 11 on the other, is used for stopping or reversing the motion of the feed either backward or forward. Each of these pulleys being furnished with a recess cast in the side, 15 in which recess is placed a spiral spring or some elastic substance. A circular plate covering the outside of these pulleys, is furnished with one projection which is inserted in this recess and presses against the spring, 20 and with another projection on the opposite or outer side facing the clutch, against which the projection of the clutch can strike. The object of this arrangement of springs or elastic substance, is, to prevent any concussion or sudden jar when shifting the motion 25 of the carriage by using the clutch.

No. 29, shaft, furnished with three pulleys, Nos. 25, 12, and 12, as hereinbefore described.

No. 30, shaft furnished with pulleys Nos. 11 and 16, clutch No. 28 and pinion gear wheel No. 23, as hereinbefore described.

No. 31, shaft furnished with pulleys Nos. 13, 14, 26, and 27 as hereinbefore described.

No. 32, shaft furnished with crank No. 7, cam No. 8, eccentric No. 43. Used for changing the vibrating carriage to a continuous feed.

Nos. 33 and 34, rods running transversely 40 through the machine to brace and hold the framework A, A, together, and also serving as pivots upon which the lower ends of the toggle jointed levers Nos. 6 $\frac{1}{2}$ move.

Nos. 35 and 36, rods running transversely 45 through the top of the machine, to brace and hold together the frame work A, A.

Nos. 37, movable and adjustable blocks of metal, fitting into the recess of the carriage E to form a cutting bed or rest for the stuff 50 while under the operation of planing or molding, so arranged that they allow the separating or cutting knives of the molding head to pass freely between them.

No. 38, elbow lever attached to bar Q and 55 arm P, at one end, the other end resting on box No. 45 and turning on a pivot in the elbow for the purpose of drawing back the bar Q and arm P, as the superior feed roller D is raised, so that the mouthpieces may be 60 regulated and always maintained at the proper relative distance (according as the stuff varies in thickness) from the cutting edge of the rotary head.

No. 39, screw nut on a hinged or joined 65 bolt to secure the caps Nos. 19 and thus hold

the axle-boxes of the rotary cutting heads firmly in place.

No. 40, screw nut to secure and hold in place the guide-braces L, L.

Nos. 41 and 41, pivoted bars which support and connect the cogwheels Nos. 20, 21, 70 and 22, and form the universal gear.

Nos. 42 and 42, movable and adjustable weights on levers T, T, by which, pressure 75 is exerted on the superior feed roller D.

Nos. 43 and 43, eccentrics on shaft No. 32 for the purpose of elevating the inferior feed roller C when the carriage E is extended so that it shall be level with the top of the carriage and act as a continuous feed roller, 80 and for the purpose of depressing the said roller so that it may be pushed back to allow the cogs of the wheel No. 48 on the side of the said roller to catch into the rack on the bottom of the carriage and thus move it 85 backward and forward in the manner hereinafter described.

No. 44, piece of metal on whose upper face the axle box No. 45 $\frac{1}{2}$ of inferior feed roller C rests and the lower face of which rests 90 upon the eccentric No. 43.

Nos. 45, ball-axle boxes of superior feed roller D.

Nos. 45 $\frac{1}{2}$, ball axle boxes of inferior feed 95 roller C.

No. 46, the molding-head (same as patented to me January 4, 1853).

No. 47, the planing or surfacing head.

No. 48, cog-gear wheels on each side of the 100 inferior feed roller C.

Nos. 49, support pieces or props, attached to weighted levers T, T, so that when the levers are raised, the supports rest on the top of the frame A, and keep the superior feed roller and the bars Q and N suspended 105 clear of the carriage, when it is vibrating back and forth in the operation of truing stuff.

Operating the machine.—Fig. 5 is a perspective view of the machine in position to 110 perform the first operation of truing, or taking out of wind, boards, planks and other carpenter stuff or for doing any kind of work in which the vibrating carriage is used. The weighted levers T, T, are elevated and secured upon the supports Nos. 49, so as to raise and keep raised the superior feed roller D, and consequently to raise and keep raised also the pressure bar N and the transverse bar Q and its mouth pieces R, R, R, R, by the means hereinbefore described, and consequently bring everything above and clear of the blades of the planing or surfacing head, which are thus the only parts of the machinery brought 115 into contact with the stuff. The guide bars 2 and 2 are now adjusted and secured by means of their screw nuts clear of the carriage. The stuff to be trued, is then dogged 120 firmly upon the wooden platform F of the 125 machine, and the machinery is then set in motion, when the stuff is trued.

carriage E. The planing or surfacing head No. 47 which is furnished with straight knives the width of the machine, is then put in rapid motion, by power applied in the usual manner. The carriage E is then projected horizontally by means of power applied to the shaft No. 31, which being connected with the shaft No. 30 by belting, moves by means of the universal gear communicating with the cogwheel No. 23, as hereinbefore described, the inferior feed roller C, whose gear-wheel No. 48 working in the rack on the under surface of the carriage E, impels it forward and brings the stuff against and under the action of the cutters throughout its entire length. The thickness of the stuff can be regulated by raising or depressing the bedpiece B, by means of the hand-wheel No. 18 as hereinbefore described.

In working and tenoning sash stuff the plank or board is cut to the length required, and then clamped upon the wooden platform F, of the carriage E. The cutting heads H, H, being fitted with knives of the proper form, are adjusted and secured as hereinbefore set forth so as to bear at once upon each end of the stuff. The machine and carriage being then set in rapid motion, the stuff is passed by and against the side cutters and thereby tenoned on both ends at once throughout its entire length. A cutting head furnished with knives of the necessary form and size is then placed in the machine and secured by the caps Nos. 19 and the screw nuts No. 39, and the stuff already tenoned as above set forth, is then run under the knives and separators of the sash cutting head, whereby the upper surface is cut throughout its entire length. The stuff is then turned, and the other side exposed to the same action, which completes and separates it, thereby requiring but three handlings to perform the same amount of work, which by the methods now in use requires from forty to fifty handlings.

Fig. 4 is a perspective view of the machine in position to perform all of the other operations requiring a continuous feed. The carriage E, is run out or extended till the projection on its side strikes, and is stopped by the hook on rod No. 10. It is now clear of the feed rollers. The shaft No. 32 is now to be turned halfway around, raising the inferior feed roller C, and the support rollers Nos. 17, and at the same time raising the lever No. 9 and causing the hooked rod No. 10 to catch the projection upon the side of the carriage E and secure the carriage firmly in its place. The props Nos. 49 are taken out from under the weighted levers T, T, so as to cause the superior feed roller D, and the back pressure bar N, and the bar Q with its mouthpieces R, R, R, R, to descend and to press upon the stuff as it passes

beneath them. The adjustable guide bars Nos. 2 are now adjusted and secured so as to guide the stuff to such part of the machine as may be desired. The molding-head No. 46, which is made with a series of alternate cutting knives of the same or various patterns, and separating saws or knives in the usual form, is now rapidly revolved by power applied in the ordinary manner. Mouthpieces R, R, R, R, cut to correspond in form with the molding knives, but of course with reversed edges are secured to the bar Q by means of screws. The movable blocks Nos. 37 are adjusted and secured so as to allow the edge of the separating saws or knives to pass freely between them, and the machine worked as in Fig. 5 is then in full operation for cutting an entire board or plank into moldings of the same or different patterns, and separating the same. Should it be desired, at the same time to rabbet, or work under the molding, one or both of the side cutters H, H, can be brought to bear by adjusting them by means of the cranes G, G, and securing them by the screw-nuts Nos. 40. When it is desired to do plain surfacing, a planing, tonguing, and grooving at once, an ordinary planing head with straight knives is inserted in place of the molding head. The side cutters can be brought to bear and the bed raised and depressed to accommodate the thickness of the stuff, in the manner set forth in describing No. 5.

It will readily be observed that this machine possesses the great advantage of being able to plane to any thickness from a quarter of an inch to fourteen inches, and of any width from one inch to twenty-four inches.

I disclaim all parts separately of the hereinbefore described machine that are not hereinafter specifically claimed by me.

What I do claim, and desire to secure by Letters Patent, is as follows, to wit:

1. I claim the arrangement as described by which the support rollers Nos. 17 and the feed roller C are raised, and the carriage E simultaneously secured, whereby I make a permanent bed and continuous feed, and by lowering the same I make a reciprocating moving bed plate or carriage and am enabled to change from one to the other at the will of the operator.

2. I claim the arrangement whereby an adjustable cutting bed No. 37 is formed on the end of the movable carriage E for the uses and purposes as described.

3. I also claim the combination and arrangement of the method herein set forth for attaching side cutters, by which they are both rendered adjustable in the manner specified and described by letters G, G, representing cranes supporting the side-cutters hanging on arms K, K, supported and adjusted by guide braces L, L, and screw-nuts

J, J, all for the purpose and in the manner set forth and described.

4. I also claim the particular arrangements in combination by which the pressure bar N, and the transverse bar Q, are made to raise, and by which they are made to correspond with the circumference of the

rotary cutter by raising the superior feed roller D for the purpose as set forth.

JOHN D. DALE.

Signed in the presence of—

W. A. ARRINGTON,
A. T. GOODMAN.
